UNITED STATES PATENT OFFICE

105,707

DESIGN FOR A BUILDING

Sally Mae Matthews, Chicago, Ill.

Application November 9, 1936, Serial No. 65,812

Term of patent 7 years

To all whom it may concern:

Be it known that I, Sally Mae Matthews, a citizen of the United States, residing at Chicago, in the county of Cook and State of Illinois, have invented a new, original, and ornamental Design for a Building, of which the following is a specification, reference being had to the accompanying drawing, forming part thereof.

The rear of the building is plain and its opposite side is similar to the side shown in Figure 3.

I claim:

The ornamental design for a building as shown and described.

SALLY MAE MATTHEWS.
